REVERSIBLE ELECTRIC SWITCH

Harry W. Brown, Mukwonago, Wis., and Raymond C. Ingels, Chicago, Ill., assignors to Cutler-Hammer, Inc., Milwaukee, Wis., a corporation of Delaware

Filed May 15, 1962, Ser. No. 70,145

Term of patent 14 years

(Cl. D26—13)

Fig. 1

Fig. 3

Fig. 4

Fig. 5

Fig. 6

FIGURE 1 is an isometric view of the front and top and left side of a reversible electric switch, showing our new design;

FIG. 2 is an isometric view of the rear and top and right side;

FIG. 3 is a front elevational view;

FIG. 4 is a side elevational view;

FIG. 5 is a top plan view; and

FIG. 6 is a rear elevational view thereof.

The dominant features of our design reside in the switch portions shown in solid lines in the drawings.

We claim:

The ornamental design for a reversible electric switch, substantially as shown and described.
